[57] **CLAIM**

The ornamental design for a signalling unit for the detection of motion, as shown and described.

DESCRIPTION

FIG. 1 is a front elevational view of signalling unit for the detection of motion showing our new design;
FIG. 2 is a rear elevational view thereof;
FIG. 3 is a left side elevational view thereof;
FIG. 4 is a right side elevational view thereof;
FIG. 5 is a top plan view thereof;
FIG. 6 is a bottom plan view thereof;
FIG. 7 is a front elevational view of a main body thereof;
FIG. 8 is a rear elevational view of a cover thereof;
FIG. 9 is a cross sectional view taken along line 9—9 of FIG. 7; and,
FIG. 10 is a cross sectional view taken along line 10—10 of FIG. 8.
